SAFETY DEVICE

Lawrence Williams and Edward J. Vosler, Dayton, Ohio, assignors to General Motors Corporation, Detroit, Mich., a corporation of Delaware

Application July 30, 1945, Serial No. 607,720

4 Claims. (Cl. 74—55)

1

This invention relates to an improved processing machine.

It is among the objects of the present invention to provide a processing machine with a safety device which prevents certain portions thereof, supported by a power device during operation of the machine, from dropping due to gravity when said power device is rendered ineffective while the machine is not utilized.

Further objects and advantages of the present invention will be apparent from the following description, reference being had to the accompanying drawings wherein a preferred embodiment of the present invention is clearly shown.

The machine, as shown in the present drawings comprises a frame having a carrier slidably attached thereto, said carrier supporting the processing tool and its operator. A prime mover, in the form of an electric motor, is carried by the frame and drives a cam. A fluid power actuated device engages the carrier and urges it to maintain a cam follower on said carrier, in contact with the working surface of the cam, the contour of which is such that during a portion of one revolution of the cam out of its rest position, the carrier will be moved by the cam in one direction against the counteracting force of the fluid power actuated device and during another portion said carrier will be moved in the opposite direction by the fluid power actuated device, under the control of the cam. The safety device, which prevents the carrier from falling due to gravity and particularly when the fluid power actuated device is deenergized, is provided by a block or lug on the cam, which is in the path of movement of the carrier cam follower when the cam is in its rest position and which is moved out of this path upon rotation of the cam.

In the drawings:

Fig. 1 shows the processing machine in side elevation.

Fig. 2 is a plan view of the machine.

Fig. 3 is a fragmentary sectional view partly in section, showing certain of the operating details of the machine.

Fig. 4 is a detail view of the control switch actuator.

Fig. 5 is a diagrammatic view showing the contour of the working surfaces of the cam.

Referring to the drawings, the machine is shown comprising a frame 20 having vertical slide-ways or gibs 21 to which the carrier 22 is slidably attached. This carrier has an angular platform 23 upon which the electric motor 24 is mounted. Suitable reduction gearing 25, driven

2

by the motor 24, drives a shaft which in turn operates the processing tool, a drill or the like, not shown in the drawings. When a cutter, broach or any type of reciprocating tool is to be used with the machine, then the motor 24 is eliminated and any suitable tool holder is attached to the platform 23.

Carrier 22 has an opening 26a in which a block 26 may be secured in vertically adjustable positions on the carrier by the pinch plate 27. An abutment 28 is provided on block 26, said abutment lying substantially in the plane of the gibs or slide-way 21. A cam-follower stud 29 is journaled in bearings 30 provided in block 26 one end of the cam follower extending from said block. When the block 26 is in its normal rest position and likewise the carrier 22, for one is secured to the other so that both move together, said block engages the one end of a rod 31, slidably supported in the frame 20, the other end of said rod engaging a resilient bumper element 32 supported in the recess 33 of the housing.

A prime mover or electric motor 40 is carried by frame 20 and has a shaft 41 extending into a compartment formed by two reinforcing walls 42 and 43 in the frame. This shaft has a worm pinion 44 secured thereto which meshes with and drives the worm wheel 45. A shaft 46 journaled in bearings 47 and 48 carried by walls 42 and 43 respectively, has the worm wheel 45 secured thereto and also a pinion 49. This pinion 49 meshes with and drives gear 50 splined to shaft 51 which is journaled in two bearings 52 and 53 carried respectively by the walls 42 and 43. The end of shaft 51 extending beyond bearing 53 has an anchor plate or disc 54 secured thereto, to which the cam 55 is bolted. The working, peripheral surface 56 of the cam is engaged by the cam follower 29 and the carrier. The contour of the working surface of cam 55 is shown by Fig. 5.

The means for urging the carrier so that the cam follower 29 thereon is maintained in constant engagement with the working surface 56 of the cam 55 comprises a fluid pressure device 60 and a lever 61 actuated thereby. To compensate for varying weight of the carrier and its equipment it sometimes is necessary to change the pivotal attachment of the lever 61 to the frame 20 for varying leverage. For this purpose lever 61 has three spaced holes 62, 63 and 64 arranged in a row longitudinally of the lever. Into any one of these holes may be inserted a bolt which is threadedly received by any one of the three holes 65, 66 or 67 arranged in a row in the frame and spaced similarly to the holes in the lever. As

shown in Fig. 1, the pivotal bolt which attaches the lever to the frame extends through the hole 63 in the lever and is threaded into the hole 66 of the frame. This makes the oppositely disposed portions of the lever substantially equal.

The fluid pressure device 60 comprises a cylinder 70 removably attached to the cover 71 of the frame, in which cylinder there is provided a piston having a rod 72 which extends outside the cylinder 70 and swivelly engages a recessed end of lever 61. The other end of said lever engages the abutment 28 of block 26, substantially in the plane of the gibs or slideway upon which the carrier 22 attached to block 26, may be reciprocated. When the device 60 is energized, that is, when fluid under pressure is introduced into the cylinder 70, the piston and its rod 72 are urged outwardly resulting in a force being exerted upon lever 61 to move it counterclockwise whereby the end of the lever, engaging the abutment 28, will urge the carrier 22 into its normal, rest position inasmuch as the force exerted by the fluid pressure device 60 and lever 61 is sufficient to overcome the weight of the carrier and the motor 40 supported thereby. Thus the cam follower 29 on the carrier is constantly urged into contact with the working surface of the cam 55 by the lever 61.

The Fig. 5 shows the contour of the cam in its normal rest position in which the cam follower 29 assumes the positions H. In this position the lug 80, formed integral with or secured to the cam, lies directly in the path of movement of the cam follower 29 and thus, if the fluid pressure device 60 is deenergized at this time and therefore eliminates the supporting function of the lever 61, the carrier and its attached elements will be prevented from dropping inasmuch as the cam follower 29 on the carrier will engage with and be supported by this lug. As the cam 55 is rotated clockwise (Fig. 5) the cam follower 29 rides over the cam surface 56a to the point where the radial line a intersects the cam surface 55 during which time and in response to such movement of the cam follower, carrier is quickly moved downwardly a predetermined distance away from its normal rest position and toward the workpiece to be processed. The cam surface 56b, extending from the radial line a to the radial line b progressively moves away from the center of the cam so that, as the cam follower traverses this portion of the cam surface the carrier is moved gradually toward the workpiece to be processed, at a definite rate and for a predetermined distance. As soon as the cam follower passes the plane of the radial line b, it will roll along the cam surface 56c which is an abrupt step-off toward the center of the cam. Now the fluid pressure device acting through the lever 61, moves the carrier and its accoutrements upwardly toward its normal rest position, this quick return of the carrier terminating when the cam follower reaches the cam surface 56d at the radial line c. The cam surface 56d between the radial lines c and d is a gentle rise pushing the cam follower against the counteracting force of the lever 61 for purposes to be described.

The end of shaft 51 extending beyond the gear 50 is splined to receive the lever 85 which may be placed upon the shaft in one of several positions rotatably, to vary its angular relation relatively to the shaft and gear. An actuator lever 86 fits over a reduced end of shaft 51 and fits flush against lever 85. An arcuate slot 87 in

lever 86 and concentric with shaft 51 receives a clamping bolt 88 the headed end of which extends through an opening in lever 85. Thus lever 86 is rotatably adjustable relatively to shaft 51 and may be secured in such adjusted position by clamping it to lever 85 which is splined to shaft 51. Lever 86, when rotating with shaft 51 engages the rod 89 to open the limit switch 90 and thus break the circuit through the holding coil (not shown) of the circuit controller 94 thereby causing said controller to break the circuit to the prime mover or electric motor 40 and stop its operation. A button 95 on the controller 94, when pressed closes the circuit controller 94 to complete a circuit to the motor 40 and causes its operation. While actuation of the switch rod 89 by lever 86 operates switch 90 to open the circuit through the holding coil of the controller 94 and thereby cause it to open the circuit to motor 40. The circuit controller 94 and the limit switch 90 are of standard design and need no detail description. The limit switch 90 is secured to the frame cover 71 in any suitable manner so that its actuator rod or member 89 may be engaged by the lever 86 and moved thereby. The limit switch is opened to stop the operation of the motor 40 when the cam follower 29 substantially reaches the position on the cam in the plane of the radial line b so that as the motor coasts to a full stop after being deenergized by the breaking of its circuit, said cam follower 29 will ride down the cam surface 56c under the effect of the fluid pressure device and its lever 61. When reaching the position in the plane of radial line c (Fig. 5) the cam follower rides on the cam surface 56d which, as has been mentioned is of gentle rise, thus the cam follower 29, in moving to the position H, is moved outwardly against the force of the lever 61. This cam follower movement occurs while the deenergized motor 40 is coasting to a stop, the counteracting forces all effecting a braking effort upon the motor which assures a full stop thereof sometime while the cam follower is riding the cam surface 56d. Now, as has been described, the lug 80 is directly in the path of movement of the cam follower 29 thereby providing a support which is engaged by and which prevents dropping of the heavy carrier and its accoutrements in the event the fluid pressure device is deenergized and does no longer provide the supporting force exerted upon the carrier 22 through the lever 61.

The type of cam used in the present invention that is, a cam whose outer peripheral surface is the working surface, offers the minimum of resistance and friction and thereby permits the use of a comparatively small motor 40 for driving the cam to actuate the carrier.

The lever 61 engaging the carrier 22 substantially in the plane of its slideway or gibs, tends to easy sliding and eliminates tilting which would increase friction. This also contributes to the use of a comparatively smaller motor for actuating the carrier.

By adjusting the pivotal connection of lever 61 to frame 20 a variable leverage may be obtained substantially to maintain the preferred ratio between the force exerted by the fluid pressure device and the weight of the carrier and its equipment.

In order to obtain different speeds of the processing tool, especially a drill or similar device rotated by the shaft 26, the operator may replace

one train of speed reducing gearing 25 with another suitable for the requirements. To change the feed speed, the gearing between the motor 40 and the cam driving shaft 51 may be altered. Various types of cams 55 may be secured to the shaft 51 to suit any condition. The machine is designed to make the said gearing easily accessible and changeable.

The interior of the frame 20 is suitably reinforced with ribs to withstand stresses and eliminate fractures when the machine is used for heavy duty work. The frame has a base portion 100 which is adapted to be secured to any desired foundation and especially to the well known rotatable indexing table upon which a plurality of these machines may be mounted each to do a specific processing job at a particular station in the rotating path of the table.

While the embodiments of the present invention as herein disclosed, constitute a preferred form, it is to be understood that other forms might be adopted, all coming within the scope of the claims which follow.

What is claimed is as follows:

1. A safety device for apparatus consisting of a reciprocative carrier held in operative engagement with the outer contour of a rotating cam by a power actuated lever whereby said carrier is moved in one direction by said lever, under the control of the rotating cam and moved in the opposite direction by the cam itself against the effect of said power actuated lever; and a detent operatively connected to the cam and held thereby in the path of carrier movement while said cam is in normal rest position, whereby automatic movement of said carrier is prevented when said lever is rendered inoperative while the cam is in normal rest position.

2. A safety device for a vertically reciprocative carrier comprising in combination, a rotatable cam; a pivoted lever; power means operative to move the lever into engagement with the carrier and urge said carrier into operative engagement with the cam whereby movement of the cam permits movement of the carrier by said lever in one direction and movement of the carrier by the cam in the other direction; and a supporting block on the cam and maintained in the path of carrier movement when said cam is in normal rest position, said block preventing dropping of the 50

carrier when the power means is rendered inoperative while the cam is at rest.

3. A safety device for a vertically reciprocative carrier comprising in combination, means operative positively to actuate said carrier in both directions said means consisting of a rotatable cam and a power actuated lever urged into constant engagement with the lower side of the carrier, the cam actuating the carrier downwardly against the effect of said power energized lever and the lever actuating said carrier upwardly against the cam; and a detent movable by said cam into the path of carrier movement and maintained in said position while said cam is in normal rest position, whereby dropping of the carrier due to deenergization of the lever while the cam is in the rest position is prevented.

4. A safety device for a vertically reciprocative carrier comprising in combination, means operative positively to actuate the carrier in both directions said means comprising a rotatable cam and a lever yieldably urged to engage the carrier and lift it into operative engagement with the cam; means operative, when energized, for urging the lever to lift the carrier; and a detent integral with the cam and moved into the path of carrier movement during a portion of a revolution of said cam, said detent preventing automatic downward movement of the carrier while the cam is in this position and the lifting effect of the lever is discontinued by rendering its energizing means ineffective.
